IRONING MACHINE

Joseph W. Jensen, Berwyn, Ill., assignor to Electric Household Utilities Corporation, Chicago, Ill., a corporation of Illinois

Application March 31, 1938, Serial No. 199,087

10 Claims. (Cl. 38—61)

This invention relates to ironing machines of the type adapted for household use, and more particularly to machines of the type comprising a rotatable roll and a cooperating power actuated shoe adapted to be automatically moved toward and away from the roll by manipulation of a suitable control member.

The invention is especially directed to a novel form of manually operable release for permitting movement of the ironer shoe away from the roll, independently of the power actuated mechanism. Devices of this general class are intended to serve the function of an emergency release, adapted to be operated primarily at a time when the motor-driven mechanism becomes stalled, such as may result from a sudden break in the electrical circuit. It can be readily appreciated that such a release is practically indispensable at times, such as when the electrical current supply is suddenly broken, because it may happen that at that particular instant, the machine may be in the process of ironing a piece of fabric or article of apparel. If releases of this type were not provided, there would be great likelihood of burning or damaging the article that happened to be passing through the machine during such a critical period.

Up to the present time, the emergency release devices provided on ironing machines have usually been associated with the arm or equivalent supporting structure for the movable shoe, and the most common form of emergency release includes an operating lever projecting upwardly adjacent the back side of the shoe, in a position which makes it necessary for the operator to reach over the hot shoe, to grasp and move the operating lever to release position. Such a release, in addition to being awkward to operate due to its location, particularly when it is desired to operate it at a critical time, also presents a serious hazard in that there is great likelihood of burning the operator's hand or arm or other portions of the body.

Another form of emergency release, which has gone into extensive commercial use, includes an operating lever located rearwardly of the shoe, adjacent the middle of its length, and projecting in a downwardly direction so as to be in a position to be engaged by the operator by reaching beneath the roll and the shoe. While this form of release does not present the hazards of the above mentioned type of release, it does, however, have another slight disadvantage in that its location is such that in ironing pieces of fabric of substantial size such as, say, a tablecloth or

sheet, a piece of the material will, when passed beyond the bight of the shoe and roll, drop down upon the support or table top, forwardly of the control lever of the emergency release, so that in the event it is necessary to operate the release at a critical time, the control lever is not visible to the operator. In fact, the material depending in front of the control lever, makes it somewhat awkward and difficult to promptly grasp the lever for quick release to prevent damage to the article being ironed, in the event the electrical current is suddenly broken, or if it happens that the machine is rendered inoperative for any other reason.

One of the objects of this invention resides in the provision of a novel form of emergency release device having a manually operable control member so located as to obviate the above mentioned difficulties which exist in connection with the present types of releases now being employed in ironing machines.

Another object resides in the provision of an improved emergency release device, which includes a manually operable control element located adjacent to the manually operable control elements for actuating the roll and shoe of the ironing machine.

A further object resides in the provision of an improved emergency release device of the character indicated, which is characterized by the provision of means adapted for resiliently moving the shoe away from the roll when the release device has been actuated.

Still another object resides in the provision of a novel and improved form of emergency release which is constructed and arranged for automatic re-engagement upon subsequent actuation of the power drive connections for actuating the shoe.

A still further object of this invention resides in the provision of an improved release of the character indicated, having means associated therewith for conveniently varying the effective pressure of the shoe against the roll.

And still another object of this invention is to provide an improved release of the character indicated, which is simple in construction, positive in operation, easily accessible for manipulation, and capable of economical manufacture.

Other objects and advantages of the present invention will be apparent from the following description, taken in connection with the accompanying drawings, in which:

Fig. 1 is a perspective view of an ironing machine embodying the present invention.

Fig. 2 is a vertical section through the driving

mechanism and release constituting the present invention, taken substantially as indicated at line 2-2 on Fig. 3.

Fig. 3 is a fragmentary horizontal section 5 through the driving mechanism and release means, taken as indicated at line 3-3 on Fig. 2.

Fig. 4 is a vertical longitudinal section, taken substantially as indicated at line 4-4 on Fig. 3.

Fig. 5 is an end view of the ironing machine 10 with a portion of the housing of the driving mechanism broken away to show the relation of the elements and with the shoe backed away from the roll to a position resulting from the operation of the emergency release.

Fig. 6 is a fragmentary sectional view through the power driven mechanism for the shoe, taken substantially as indicated at line 6-6 on Fig. 3.

Fig. 7 is a fragmentary sectional view taken at line 7-7 on Fig. 6, showing the manually operable linkage for controlling the driving mechanism which actuates the shoe.

For purpose of illustration, I have shown the present invention embodied in an ironing machine of the "table top" type, comprising a table-like supporting structure 10, which is preferably formed of sheet metal, and on which is mounted a suitable housing indicated generally at 11, for enclosing the driving mechanism. Associated with and supported by said housing is a horizontally extending rotatable roll 12, and mounted rearwardly of the roll and extending substantially the length thereof is a shoe 14 which is adapted to be mechanically moved into and out of cooperating relation with said roll by means 25 to be hereinafter described. It is to be understood that the shoe 14, which includes a conventional sole plate 15, may be heated in any suitable manner, such as electrically or by gas. The shoe is supported adjacent the middle of its 30 length by means of a clevis bracket 17, which is pivotally connected by a pin 18 to the upper end of an upwardly extending arm 19, which arm is rigidly secured at its lower end, by means of a pin 20, to the outer end of a horizontally extending rock shaft 21, supported adjacent the top of the table structure 10. As seen in Fig. 4, said rock shaft is journaled at one end in the housing 11 while its opposite end is journaled in a bracket 23 rigidly secured to the top of the 35 table structure 10, preferably adjacent the rock arm 19. Said arm 19 is provided with a spring-pressed button 19^a adapted to engage the lower portion of the rear surface of the housing of the shoe 14 for supporting said shoe in a position 40 for proper engagement with the roll 12.

The roll 12 may be driven in any suitable manner and as herein shown, a motor 25 is supported below the top of the table support 10 and may be understood to be operably associated with a suitable worm gear reduction unit, which is arranged to drive a vertically disposed shaft 27, which projects upwardly through a tubular standard 28, which is rigidly attached by means of screws 29 to a horizontally extending wall 30, which is 45 formed as an integral part of the interior of the housing 11. The upper portion of said shaft 27 is rigidly connected by a key 32 to a clutch member 33 having a tubular depending portion journaled in a bearing 34 mounted in the upper end 50 of said tubular support 28, as seen in Fig. 2. The extreme upper end of the shaft 27 is formed with a socket 27^a for receiving a correspondingly formed projection 36^a of a vertically aligned shaft 36, the upper portion of which is formed with a 55 worm 37 operatively meshed with a worm wheel

38 mounted on a shaft 39 for driving the roll 12 through the medium of suitable clutch means (not shown), and which may be understood to be controlled by an operating member 40, extending from the front wall of the housing 11. The clutch for driving the roll 12, does not constitute any part of the present invention and, therefore, is not illustrated or described. It is to be understood that it may be one of several types of clutch units as now embodied in the various commercial ironing machines that are being marketed. The lower portion of the worm shaft 36, together with the upper portion of the shaft 27, are journaled in a tubular drive element 43, the upper portion of which is journaled in 10 a bearing 44 in the upper portion of the housing 11. The lower end of the tubular drive member 43 abuts against the upper end of clutch member 33, and the lower portion of the drive member is formed with a plurality of circumferentially spaced-apart splines 46, on which is slidably mounted a clutch member 48 having jaws 48^a adapted to cooperatively engage with the jaws 33^a of the clutch member 33. It is by virtue of this clutch, the operation of which will herein-after be described, that the shoe 14 is adapted, upon operation of a manual control, for first moving into cooperative engagement with the roll 12, and upon the next successive operation of the control element to be backed away from the roll 12 to a position coincident with that indicated in Fig. 5.

Rigidly mounted on the tubular drive element 43, above the clutch element 48, by means of a key 50 is an eccentric 51, surrounded by an eccentric strap 52, which, as seen in the drawings, is disposed in a substantially horizontal plane. The outer end of the strap 52 is pivotally connected, by a pair of transversely spaced-apart links 53, to a trunnion element 55, having a depending portion 55^a journaled and secured in the upper end of an upwardly extending driving arm 57, which is loosely mounted adjacent the end of the portion of the rock shaft 21 which extends into the housing 11. Immediately adjacent arm 57 is a yoke arm 58 rigidly secured to the shaft by a pin 59. Said yoke arm includes a pair of axially spaced-apart walls 60 which provide the journal support for said arm on the rock shaft 21. Loosely mounted on the rock shaft intermediate said walls 60 of the arm 58 is an upstanding lever arm 62 in which is adjustably threaded a bolt 64, one portion of which extends freely through a slot 65 formed in the upper portion of the back wall of the yoke arm 58. A pre-loaded compression spring 67 is mounted on said rearwardly extending portion of the bolt and reacts against the outer surface of the back wall of the yoke arm 58, and against the underside of the nut 68, which is fixedly mounted on the extreme end of said bolt. The opposite end of the bolt extends into a cavity 70 formed in the adjacent end of a horizontally extending control member 71, the opposite end of which member is journaled in a bracket 72 and protrudes through the front wall of the housing 11, and is provided with a finger-piece or knob 73 for convenient actuation. Said member 71 is capable of axial and rotative movement and is normally retained in the position seen in Fig. 2 by means of a coil spring 75, reacting between the bracket 72 and a pin 76 extending through said member interiorly of the front wall of the housing 11.

The forward portion of the bolt 64 is provided

with a transversely extending pin 78, which projects laterally through diametrically opposite longitudinally extending slots 79 formed in the wall of the member 71 which defines the cavity 70. By virtue of this arrangement, the bolt, together with the lever arms 58 and 62, are free for movement as a unit, with the rock shaft 21, independently of axial movement of the member 71. Said connection of the bolt 64 and member 71 by means of the transversely extending pin 78 permits varying the pressure of spring 67 which, in turn, varies the effective pressure of the shoe 14, against the roll 12, as will be hereinafter described. Mounted in the upper portion 15 of the driving arm 57 is a horizontally extending pin 81 on which is pivotally mounted a latch member 82, having a hook portion 83 adapted to engage the upper edge of the loose arm 62 which carries the bolt 64, for latching said arms 57, 58, and 62 together as a unit.

The eccentric 51 is intermittently driven and at each operation of a control member 102 rotates a half revolution and through the connections of the drive arm 57, latch 82, lever 62, bolt 64, spring 67, and yoke lever 58, causes rocking of the rock shaft 21 for moving the shoe either into or out of cooperative engagement with the roll 12. The operation of the eccentric is controlled through the tubular drive member 43 and the clutch member 48, on which an annular cam element 85 is externally mounted and rigidly secured thereto by a pin 86. The lower edge of the cam element 85 is of irregular contour, constituting two diametrically opposite cam surfaces 85^a, which terminate in two oppositely arranged depending stops 87 for arresting rotation of the clutch element 48 when same is disengaged from the clutch element 33. Cooperating with the cam surfaces 85^a is a horizontally disposed pin 88 which is mounted in an opening 89 formed in a boss 11^a protruding inwardly from the inner surface of the removable end wall 11^b of housing 11. The outer end of the pin 88 is formed with a cavity 90 in which is pocketed a coil spring 91 reacting against the outer wall of the housing portion 11^b for urging the pin inwardly into position for engagement with either of the cam surfaces 85^a of the cam 85. Mounted below the pin 88 in the opening 89 is a block 93 which is urged in an upwardly direction by a coil spring 94 acting through the detent 95, which engages in a notch 96 formed in the block 93 and which serves to maintain the inner end of the pin 88 in yielding engagement with either the cam surfaces 85^a. Said pin adjacent its inner end is formed with a pair of axially spaced collars 97 between which extends the ends of a forked element 98 rigidly secured to a rock shaft 99, which is journaled at one end in a bearing bracket 100 formed integrally with the boss 11^a of the housing, while the opposite end of the shaft 99 protrudes through the front wall of said housing, as seen in Figs. 3 and 7, and is provided with a finger-piece 102 which, when depressed, rocks the shaft 99 for retracting the pin 88, against the reaction of spring 91, and permitting the clutch member 48, together with the cam 85 to drop downwardly so that the clutch jaws 48^a are positioned for driving engagement with the clutch jaws 33^a of the clutch member 33. To insure that the clutch member 48 will move downwardly when released by the pin 88, I provide a relatively light coil spring 103 for reacting against the upper end of said member and against the underside of the eccentric 51. It will now be apparent that when

the finger-piece 102 is depressed to withdraw pin 88, permitting the clutch member 48 to move into driving engagement with the clutch member 33, rotation is imparted to the tubular drive element 43 which, in turn, causes rotation of the eccentric 51. Due to the formation of the cam surfaces 85^a, the pin 88, which is spring-pressed inwardly by the spring 91, is positioned for causing the cam together with the clutch member 48 to become axially raised out of engagement with clutch member 33 upon completion of a half revolution of the tubular drive element 43, and the clutch member 48 becomes positively arrested by the abutment 87 striking against the pin 88. It will now be apparent that each time the finger-piece 102 is depressed, rocking the shaft 99, the eccentric 51 is rotated one-half revolution and which, through the lever arms 57, latch 82, and the lever arms 58 and 62, which are connected by the bolt 64, causes rocking of the rock shaft 21, for moving the shoe into and out of cooperative engagement of the roll.

Because of the arrangement of the lever arms and their connection to the eccentric, it will be apparent that additional means will be required for insuring return movement of the shoe away from the roll, and for this purpose I provide a tension spring 105, which is connected to lever 58 and the interior of the housing 11. The pressure of the coil spring 67 is rendered ineffective during the rearward movement of the levers 57 and 62 by the action of the eccentric, so as to permit rearward movement of the yoke arm 58 by the spring 105, for rocking the shaft 21, and arm 19, rearwardly to back the shoe 12 away from the roll. To limit such rearward movement, the interior of the housing 11 is provided with an inclined stop surface 11^c, which is adapted to be engaged by the outer end of the bolt 64 for arresting the rearward movement of the arm 19 and the shoe 14.

To insure positive movement of the shoe away from the roll in the event of an emergency, such as when the electrical current supply circuit is suddenly broken, the operator merely needs to push the control knob 73 inwardly, as seen in Fig. 5, by virtue of which movement the inner end of the member 71 will be caused to engage the depending leg 82^a of the latch member 82 and swing the latch about its pivot, as seen in Fig. 5, for disengaging its connection with the lever 62 and which, due to the pre-loaded condition of the spring 67, instantly releases the levers so that spring 105 becomes free to act on the lever 58 for rocking the shaft and swinging the arm 19 with the shoe rearwardly to the position seen in Fig. 5. After such operation of the control member 71, said member is returned to normal position by the spring 15 and it will be manifest that upon re-establishment of the electric circuit and the next successive actuation of the finger-piece 102, the eccentric will be caused to move to a position so that the latch member 82 will automatically drop by gravity into latched relation with the upper end of the lever arm 62; and then the next subsequent actuation of the finger-piece 102 will cause the eccentric acting on the lever arms 57, 58, and 62 to positively rock the shaft 21, forwardly to move the shoe into cooperative relation with the roll.

In ironing various articles of wearing apparel and other fabric material, such as tablecloths, linens, etc., it is frequently desired to vary the effective pressure of the shoe against the roll 12. For this purpose I have provided a convenient

arrangement which merely requires the rotation of the knob 73 in one direction or the other which, through the member 71, causes rotation of the bolt 64 by reason of the inter-connection of the pin 78 in the slots 79 so that the bolt is caused to rotate for either increasing or decreasing the tension on the coil spring 67.

It will now be observed that by virtue of the construction constituting the present invention, 10 all operating controls for the machine are conveniently located in a group so as to be readily accessible by one hand of the operator, without any appreciable bodily movement from the position normally occupied in performing ironing 15 operations on the machine. The location of the emergency release adjacent the other controls for both the shoe and the roll of the ironing machine definitely eliminates all possibility of injury to the operator, in operating the release, as 20 well as obviates any danger of valuable pieces of fabric that are being ironed from becoming damaged in the event that the ironing machine is suddenly rendered inoperative, such as by breaking 25 of the current supply circuit.

25 Although I have shown and described a preferred embodiment of my invention, manifestly it is capable of modification and rearrangement of parts without departing from the spirit and scope thereof, and it is to be understood that the 30 particular type and arrangement of driving mechanism for the rolls and shoe, herein disclosed, is merely for the purpose of illustration. I do not, therefore, wish to be understood as limiting this invention to the precise embodiment 35 herein disclosed, except as it may be so limited by the appended claims.

I claim as my invention:

1. In an ironing machine, the combination with a rotatable roll, a shoe movable into and 40 out of cooperative engagement with the roll, manually controlled power driven means for actuating said roll and moving the shoe toward and away from the roll, and a housing enclosing said power driven means; of a rock shaft extending 45 in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, detachable driving connections in said housing, between said power driven 50 means and the rock shaft, and manually operable means for releasing said driving connections for enabling the rock shaft and arm to move the shoe out of engagement with the roll, said detachable driving connections including means rendered operable upon subsequent operation of 55 the power driven means for re-establishing operating connections to the rock shaft.

2. In an ironing machine, the combination with a rotatable roll, a shoe movable into and 60 out of cooperative engagement with the roll, manually controlled power driven means for actuating said roll and moving the shoe toward and away from the roll, and a housing enclosing said power driven means; of a rock shaft extending in a direction parallel to said roll and 65 having one end extending into and having journaled support in said housing, an upwardly extending arm rigidly mounted on the other end of said shaft and having its upper end directly connected to said shoe for supporting and moving it into and out of engagement with the roll,

upon rocking of said shaft, intermittently operated driving connections in said housing, between said power driven means and the rock shaft for controlling the movement of the shoe into and out of engagement with the roll, manually actuated emergency release means, interconnected with said driving connections and operable at will, for disengaging said driving connections, and means independently of and operable upon release of said driving connections for moving the 10 shoe out of engagement with the roll.

3. In an ironing machine, the combination with a rotatable roll, a shoe movable into and out of cooperative engagement with the roll, manually controlled power driven means for actuating said 15 roll and moving the shoe toward and away from the roll, and a housing enclosing said power driven means; of a rock shaft extending in a direction parallel to said roll and having one end extending into and having journaled support in 20 said housing, an upwardly extending arm rigidly mounted on the other end of said shaft and having its upper end directly connected to said shoe for supporting and moving it into and out of engagement with the roll, upon rocking of said 25 shaft, intermittently operated driving connections in said housing, between said power driven means and the rock shaft for controlling the movement of the shoe into and out of engagement with the roll, manually actuated emergency release means, 30 operable at will, for disengaging said driving connections, and spring means, independent of said power driven means, operable upon release of said driving connections for rocking said shaft in a rearward direction, causing said arm to move 35 the shoe out of engagement with the roll.

4. In an ironing machine, the combination with a rotatable roll, a shoe movable into and out of cooperative engagement with the roll, manually controlled power driven means for actuating said 40 roll and moving the shoe toward and away from the roll, and a housing enclosing said power driven means; of a rock shaft extending in a direction parallel to said roll and having one end extending into and having journaled support in 45 said housing, an upwardly extending arm rigidly mounted on the other end of said shaft and having its upper end directly connected to said shoe for supporting and moving it into and out of engagement with the roll, upon rocking of said 50 shaft, intermittently operated driving connections in said housing, between said power driven means and the rock shaft, for controlling the movement of the shoe into and out of engagement 55 with the roll, spring means acting on the rock shaft and adapted when said shaft moves the shoe into engagement with the roll for exerting substantial yielding pressure of the shoe against the roll, and manually operable emergency release means, having an operating portion exteriorly of the housing, for releasing said driving 60 connections for enabling the rock shaft and arm to move the shoe out of engagement with the roll, said manually operable emergency release 65 means having interconnections with said spring means for adjustment with respect to each other for varying the pressure of the shoe against the roll.

5. In an ironing machine, the combination with 70 a rotatable roll, a shoe movable into and out of the cooperative engagement with the roll, manually controlled power driven means for actuating said roll and moving the shoe toward and away from the roll, and a housing enclosing said power 75

- driven means; of a rock shaft extending in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, intermittently operated driving connections in said housing, between said power driven means and the rock shaft, for controlling the movement of the shoe into and out of engagement with the roll, spring means acting on the rock shaft and adapted when said shaft moves the shoe into engagement with the roll for exerting substantial yielding pressure of the shoe against the roll, manually operable emergency release means having an operating portion exteriorly of the housing, for releasing said driving connections, said manually operable emergency release means having interconnections with said spring means for adjustment with respect to each other for varying the pressure of the shoe against the roll, and spring means acting on said rock shaft, adapted upon release of the driving connections, for causing rocking of said shaft rearwardly for moving the shoe out of engagement with the roll.
6. In an ironing machine, the combination with a rotatable roll, a shoe movable into and out of cooperative engagement with the roll, manually controlled power driven means for actuating said roll and moving the shoe toward and away from the roll, and a housing enclosing said power driven means; of a rock shaft extending in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, intermittently operated driving connections in said housing, between said power driven means and the rock shaft, for controlling the movement of the shoe into and out of engagement with the roll, spring means acting on the rock shaft and adapted when said shaft moves the shoe into engagement with the roll for exerting substantial yielding pressure of the shoe against the roll, manually operable emergency release means, having an operating portion exteriorly of the housing, for releasing said driving connections, said manually operable emergency release means having interconnections with said spring means for adjustment with respect to each other for varying the pressure of the shoe against the roll, spring means acting on said rock shaft, adapted upon release of the driving connections, for causing rocking of said shaft rearwardly and moving the shoe out of engagement with the roll, and stop means for limiting said rearward movement of the rock shaft and thereby limiting rearward movement of the shoe.
7. In an ironing machine, the combination with a rotatable roll, a shoe movable into and out of the cooperative engagement with the roll, manually controlled power driven means for actuating said roll and moving the shoe toward and away from the roll, and a housing enclosing said power driven means; of a rock shaft extending in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, intermittently operated driving connections in said housing, between said power driven means and the rock shaft, for controlling the movement of the shoe into and out of engagement with the roll, spring means acting on the rock shaft and adapted when said shaft moves the shoe into engagement with the roll for exerting substantial yielding pressure of the shoe against the roll, manually operable emergency release means having an operating portion exteriorly of the housing, for releasing said driving connections, said driving connections including means for automatically re-establishing operating connections upon subsequent operation of said power driven means for moving the shoe, said manually operable emergency release means having interconnections with said spring means for adjustment with respect to each other for varying the pressure of the shoe against the roll, and spring means acting on said rock shaft, adapted upon release of the driving connections for causing rocking of said shaft rearwardly for moving the shoe out of engagement with the roll.
8. In an ironing machine, the combination with a rotatable roll, a shoe movable into and out of cooperative engagement with the roll, power driven means for actuating said roll and shoe, and a housing enclosing said power driven means; of a rock shaft extending in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, detachable driving connections, in said housing, between said power driven means and the rock shaft, said connections including a driving arm rigidly mounted on the rock shaft, an upstanding arm loose on the shaft and having a portion disposed in overlapping relation to said driving arm, a bolt threaded in said last mentioned arm and projecting through an opening in the driving arm, a pre-loaded coil spring on the bolt acting on the driving arm, a lever arm positively connected to the driving means and loosely mounted on the rock shaft adjacent the two last mentioned arms, means for latching the two loose arms together whereby actuation of the driving means moves the shoe toward the roll and said pre-loaded spring yieldingly presses said shoe against the roll, and manually operable means for disengaging the latch means for enabling the shoe to be moved away from the roll.
9. In an ironing machine, the combination with a rotatable roll, a shoe movable into and out of cooperative engagement with the roll, power driven means for actuating said roll and shoe, and a housing enclosing said power driven means; of a rock shaft extending in a direction parallel to said roll and having one end extending into and having journaled support in said housing, an upwardly extending arm rigidly mounted on the other end of said shaft and having its upper end directly connected to said shoe for supporting and moving it into and out of engagement with the roll, upon rocking of said shaft, detachable driving connections, in said housing, between said power driven means and the rock shaft, said

connections including a driving arm rigidly mounted on the rock shaft, an upstanding arm loose on the shaft and having a portion disposed in overlapping relation to said driving arm, a bolt threaded in said last mentioned arm and projecting through an opening in the driving arm, a pre-loaded coil spring on the bolt acting on the driving arm, a lever arm positively connected to the driving means and loosely mounted on the rock shaft adjacent the two last mentioned arms, means for latching the two loose arms together whereby actuation of the driving means moves the shoe toward the roll and said pre-loaded spring yieldingly presses said shoe against the roll, and manually operable means for disengaging the latch means for enabling the shoe to be moved away from the roll, said latch disengaging means and bolt being interconnected, whereby to cause rotation of the latter by the former for varying the pressure of said pre-loaded spring.

10. In an ironing machine, the combination with a rotatable roll, a shoe movable into and out of cooperative engagement with the roll, power driven means for actuating said roll and shoe, and a housing enclosing said power driven means; of a rock shaft extending in a direction parallel to said roll and having one end extending into and having journaled support in said housing, an upwardly extending arm rigidly

mounted on the other end of said shaft and having in its upper end directly connected to said shoe for supporting and moving it into and out of engagement with the roll, upon rocking of said shaft, detachable driving connections, in said 5 housing, between said power driven means and the rock shaft, said connections including a driving arm rigidly mounted on the rock shaft, an upstanding arm loose on the shaft and having a portion disposed in overlapping relation to said 10 driving arm, a bolt threaded in said last mentioned arm and projecting through an opening in the driving arm, a pre-loaded coil spring on the bolt acting on the driving arm, a lever arm positively connected to the driving means and 15 loosely mounted on the rock shaft adjacent the two last mentioned arms, means for latching the two loose arms together whereby actuation of the driving means moves the shoe toward the roll and said pre-loaded spring yieldingly presses 20 said shoe against the roll, manually operable means for disengaging the latch means for enabling the shoe to be moved away from the roll, and separate spring means, adapted upon disengagement of the driving connections, for rocking 25 said shaft in a rearward direction, and simultaneously moving the shoe out of engagement with the roll.

JOSEPH W. JENSEN.
